[57] **CLAIM**

The ornamental design for a headset for use in applying electrical signals to the temples, as shown and described herein.

DESCRIPTION

FIG. 1 is a top, right and rear perspective view of the headset for use in applying electrical signals to the temples, showing my new design with a headband and electrical wire being shown in broken lines for illustrative purposes only;

FIG. 2 is a bottom, left and front perspective view thereof;

FIG. 3 is a top plan view thereof shown on a reduced scale;

FIG. 4 is a left side elevational view thereof shown on a reduced scale;

FIG. 5 is a bottom plan view thereof shown on a reduced scale;

FIG. 6 is a front elevational view thereof shown on a reduced scale;

FIG. 7 is a rear elevational view thereof shown on a reduced scale;

FIG. 8 is a right side elevational view thereof shown on a reduced scale;

FIG. 9 is a cross-sectional view thereof taken along line 9—9 of FIG. 3;

FIG. 10 is a cross-sectional view thereof taken along line 10—10 of FIG. 3;

FIG. 11 is a top, right and rear perspective view of the headset for use in applying electrical signals to the temples, showing a second embodiment of my new design;

FIG. 12 is a bottom, left and front perspective view thereof;

FIG. 13 is a top, right and rear perspective view of the headset for use in applying electrical signals to the temples, showing a third embodiment of my new design;

FIG. 14 is a bottom, left and front perspective view thereof.

FIG. 1.

FIG. 2.

FIG. 3.

FIG. 6.

FIG. 9.

FIG. 10.

FIG. 4.

FIG. 7.

FIG. 5.

FIG. 8.

FIG. 11.

FIG. 12.

FIG. 13.

FIG. 14.
